UNITED STATES PATENT OFFICE.

CHARLES GIBFORD, OF PONTIAC, MICHIGAN, ASSIGNOR TO GENERAL MOTORS CORPORATION, OF DETROIT, MICHIGAN, A CORPORATION OF DELAWARE.

VALVE MECHANISM.

Application filed July 28, 1921. Serial No. 488,225.

To all whom it may concern:

Be it known that I, CHARLES GIBFORD, a citizen of the United States, and a resident of Pontiac, county of Oakland, and State of Michigan, have invented certain new and useful Improvements in Valve Mechanism, of which the following is a full, clear, concise, and exact description, such as will enable others skilled in the art to which the invention relates to make and use the same, reference being made therein to the accompanying drawings, which form a part of this specification.

The invention relates to valve mechanism, and while in some respects of more general application, it has been designed with particular reference to use in connection with an air heater of the type employed in supplying heated air to a carbureter of an internal combustion engine.

The invention has for its principal object the provision of an improved valve mechanism capable of being easily and cheaply manufactured and assembled and being easy of adjustment and efficient in operation.

A further object is the provision of a valve structure comprising in a single piece a valve member proper and a spindle or shaft therefor, the whole being formed by suitable bending operations from a unitary sheet metal blank.

A further object is the provision of an improved handle and locking device whereby the valve spindle may be rotated and whereby it may be retained in the desired positions of adjustment.

Further objects and advantages will appear from the following description taken in connection with the accompanying drawings, in which—

Fig. 1 is a side elevation of an internal combustion engine showing in connection therewith one embodiment of my invention;

Fig. 2 is a cross section on line 2—2 of Fig. 1;

Fig. 3 is an elevation of the air conduit shown in Fig. 1 taken from the right end;

Fig. 4 is a plan view and Fig. 5 an end elevation of the valve member;

Fig. 6 is a plan view of the blank from which the valve member is formed; and

Fig. 7 is a plan view of the combined handle and locking device applied to a slightly different form of valve member.

Referring to the drawings, 10 indicates an internal combustion engine including the intake manifold 11, an exhaust manifold 12, and carbureter 13. A heating device, ordinarily termed a stove, is provided for heating the air supplied to the carbureter intake 14, which stove may comprise, as shown, a jacket or bell 15 surrounding a part of the exhaust manifold and connected by a branched conduit 16 to the air intake 14, one branch of the conduit opening directly to the air, as at 17. A valve member of suitable form, as the butterfly valve 18, is pivotally mounted, as at 19, in such position that by rotation or oscillation of the valve 70 it may be positioned either to close the opening of the conduit 17 or the branch leading to the heating jacket 15. The valve therefore provides a means whereby heated air 75 may be supplied to the carbureter or the air may be taken directly from the exterior without preheating.

The valve mechanism with which my invention is more directly concerned comprises a valve member proper as shown at 80 18 and a spindle or shaft therefor indicated at 20. I form the valve preferably by bending operations from a sheet metal blank of the form illustrated in Fig. 6 comprising a shaft portion 20' of suitable dimensions to provide, when bent to tubular form, the spindle 20 and an extension 18' of suitable form to close the passage with which the valve may be associated. It will be noted that the shaft portion 20' has projecting 90 portions extending in both directions beyond the portion 18', as at 21', 22', which extensions, when the shaft portion is bent to tubular form, serve as journals 21, 22 adapted to seat within suitable apertures in 95 the walls of a conduit to provide pivotal support for the valve member.

In order to rotate the valve, I provide a handle 23 formed preferably from resilient material, as from spring wire. One end of the handle may be formed with a loop 24 having a hooked end 25, the other end being provided with a suitably shaped portion, as a loop 26, whereby the handle may be seized and the valve rotated to the desired positions of adjustment. A slot 27 is provided in one side of the journal portion 22 through which the handle 23 may be passed to such position that the loop 24 is allowed to extend outwardly from the 110

journal 22 with the hook 25 engaging the end of the slot to thereby prevent displacement of the handle. An aperture 28 is formed in the journal portion 22 opposite the slot 27, which aperture may be constituted by two notches 28' in the mating edges of the blank portion 22' and through which aperture the handle 23 extends. The handle will be made preferably of such length as to extend outwardly over the curved surface of the conduit with which the valve is associated and will be bent in such manner as to contact resiliently with such conduit. The frictional engagement of the handle with the walls of the conduit will therefore tend to retain the valve in the desired positions of adjustment, particularly if, as illustrated in Fig. 1, the shape of the conduit is such that the tendency of the handle to slide downwardly over the curved surface of the conduit will cause the valve member to move toward its closed position at the respective extremes of its movement. By merely grasping the loop 26, however, the handle may be readily bent away from the seated position against the conduit and the valve may then be rotated to the opposite extreme of its movement, where it will be resiliently retained upon releasing the handle.

Where a valve of the form illustrated in Fig. 7 is employed, comprising a valve member 29 secured to a spindle 30 as by screws 31, the spring handle 23' may be attached to the spindle by the provision of a loop 24' lying in a plane at right angles to the plane of the loop 26 and secured to the spindle 30 as by clamping it between the nuts 31. The operation in this case will be the same as that already described, in that the resilient portion of the handle 23' engaging the walls of the conduit with which the valve is associated will tend to retain the valve resiliently in its extreme positions.

Various other changes may be made in details of construction and operation without departing from the spirit and scope of

the invention and therefore I do not wish to be limited to the specific structure herein set forth except as required by the language of the appended claims in view of the prior art.

I claim:

1. In valve mechanism, the combination of a conduit having curved walls, a valve therein having two extreme positions of adjustment, and a resilient handle for said valve shaped to engage said curved walls and thereby retain the valve in either of its positions.

2. In valve mechanism, the combination of a branched conduit, a valve pivoted in said conduit in position to close either of its branches, a handle comprising a resilient wire connected to said valve, said handle shaped to engage opposite sides of said conduit when the valve is in its respective positions and adapted, by engagement with the conduit, to force the valve resiliently to its extreme positions.

3. In valve mechanism, the combination with a valve member comprising a flow-obstructing portion and a spindle portion formed from a single piece of sheet material, said spindle portion having apertures therethrough, of a handle member comprising a resilient device seated in said apertures.

4. The combination with a member to be rotated comprising a spindle formed by bending sheet material into tubular form, said spindle having apertures upon opposite sides thereof, of a handle comprising a resilient wire bent to form to pass through said apertures and be retained therein.

5. In valve mechanism, a valve member mounted for pivotal movement about one edge thereof, said member comprising a body portion and a shaft portion formed from a blank of sheet material, the shaft portion being constituted by a part of the blank extending beyond the body portion in the direction of the pivot and bent to form a spindle.

In testimony whereof I affix my signature.

CHARLES GIBFORD.
